STANLEY GRILLO AND JOSEPH GUERRA, OF TUCKAHOE, NEW YORK.

ANIMATED WIND-OPERATED ORNAMENT.

Application filed September 28, 1926. Serial No. 138,251.

This invention relates to ornaments particularly but not necessarily designed for automobile radiator caps, and comprehends an animated wind-operated ornament which is highly attractive in appearance, comparatively simple in construction and inexpensive to manufacture.

More specifically the invention contemplates an animated ornament of the character set forth which includes a supporting or bearing bracket in which a crank shaft is mounted and upon the crank portions of which representative figures are arranged together with wind-operated means for driving the crank shaft to impart animation to the representative figures.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a perspective view of the ornament as applied to an automobile radiator cap;

Fig. 2 is a plan view thereof;

Fig. 3 is a sectional view taken approximately on the line 3—3 of Fig. 2, and

Fig. 4 is a fragmentary view taken approximately on the line 4—4 of Fig. 2.

Referring to the drawings by characters of reference, 10 designates a bracket which is of substantially U-shaped formation presenting spaced parallel vertical arms 11—11. Adjacent the upper end, the arms are formed with aligned bearing openings 12—12 through which the shaft 13 extends to mount the shaft for free rotation in the bracket.

45 A sleeve 14 is arranged over the shaft 13 between the arms 11—11 and said sleeve is formed with a central enlarged portion or hub 15 having radial slots 16 receiving the stems or shanks 17 of cup-shaped blades 18 which constitute means for turning the shaft by wind pressure.

The outer extremities of the shaft 13 have secured thereto diametrically opposite projecting crank arms 19 upon the crank pins 20 of which representative figures 21 are journaled. Attached to each representative figure is an arm 22 having an angularly inwardly bent terminal 23 engaged in a slot 24 of the respective arm 11, to provide means for setting up a rocking motion to the representative figures when the shaft is rotated, so as to lend animation to said figures while limiting the rotatory movement thereof.

From the foregoing it will be seen that a highly attractive, ornamental and amusing device has been provided which is simple in its construction and inexpensive to produce.

What is claimed is:

1. An animated wind-operated ornament including a crank shaft, a wind-wheel secured to the crank shaft for rotating the same, a representative figure attached to the crank portion of said shaft for movement thereby, and means for limiting the rotary movement of the figure to impart a rocking motion thereto, said means including a slotted stationary bearing element for the crank shaft, and an arm provided on the representative figure having an offset terminal engaging and movable in the slotted portion.

2. An ornament of the character described, including a bearing bracket having a pair of spaced parallel arms having aligned bearing openings, a shaft journaled for rotation in the bearing openings and having oppositely disposed crank terminals, representative figures journaled on the crank terminals, a wind-wheel connected with the shaft for rotating the same, and means for limiting the representative figures to a rocking movement upon rotation of the shaft, consisting of slotted portions in the bearing bracket arms, and arms on the representative figures having offset terminals engaging and movable in said slotted portions.

STANLEY GRILLO.
JOSEPH GUERRA.
